(57) **CLAIM**

The ornamental design for an electro-heating apparatus as shown and described.

DESCRIPTION

FIG. 1 is a front view of an electro-heating apparatus in an extended state;

FIG. 2 is a rear view of the electro-heating apparatus of FIG. 1 in the extended state;

FIG. 3 is a front perspective view of the electro-heating apparatus of FIG. 1 in the extended state;

FIG. 4 is a rear perspective view of the electro-heating apparatus of FIG. 1 in the extended state;

FIG. 5 is a side view of the electro-heating apparatus of FIG. 1 in the extended state;

FIG. 6 is a front view of the electro-heating apparatus of FIG. 1 in a retracted state;

FIG. 7 is a rear view of the electro-heating apparatus of FIG. 1 in the retracted state; and,

FIG. 8 is a front perspective view of the electro-heating apparatus of FIG. 1 in the retracted state.
